US00D831595S

(12) **United States Design Patent** (10) **Patent No.:** **US D831,595 S**
Mittleman et al. (45) **Date of Patent:** **** Oct. 23, 2018**

(54) **MAGNET MOUNT**

(71) Applicant: **GOOGLE LLC**, Mountain View, CA (US)

(72) Inventors: **Adam Duckworth Mittleman**, Redwood City, CA (US); **Jason Evans Goulden**, Los Gatos, CA (US); **Nicholas Webb**, Menlo Park, CA (US); **Gregory Daniel Louis Germe**, Oakland, CA (US); **William Raeming Dong**, Palo Alto, CA (US); **Rochus Jacob**, San Francisco, CA (US); **Poll Shih**, New Taipei (TW)

(73) Assignee: **GOOGLE LLC**, Mountain View, CA (US)

(**) Term: **15 Years**

(21) Appl. No.: **29/570,406**

(22) Filed: **Jul. 7, 2016**

(51) LOC (11) Cl. **13-99**

(52) U.S. Cl.

USPC **D13/183**

(58) **Field of Classification Search**

USPC D13/183; D9/418; D6/314; D21/311-323, 398, 404, 478, 484-505; 446/92

CPC A63H 33/04; A63H 33/046; A63F 2009/1033

See application file for complete search history.

(57) **CLAIM**

The ornamental design for a magnet mount, as shown and described.

DESCRIPTION

FIG. 1 is a top perspective view of our new design of a magnet mount;

FIG. 2 is a bottom perspective view thereof;

FIG. 3 is a top view thereof;

FIG. 4 is a bottom view thereof;

FIG. 5 is a first side view thereof;

FIG. 6 is a second side view thereof; and,

FIG. 7 is a third side view thereof.

The broken lines, including those showing a logo, in the above described FIGS. 1-7 are for illustrative purposes only, depict environmental matter only, and form no part of the claimed design.

1 Claim, 7 Drawing Sheets
